(57) CLAIM

The ornamental design for a fondue apparatus, as shown and described.

DESCRIPTION

FIG. 1 is a top and side perspective view of a fondue apparatus showing my new design;

FIG. 2 is a side elevational view thereof;

FIG. 3 is a top and side perspective view of the casserole alone, of the fondue apparatus;

FIG. 4 is a side elevational view of the casserole alone, the side opposite that shown in FIG. 4 being identical thereto;

FIG. 5 is a top plan view of the casserole alone;

FIG. 6 is a bottom plan view of a cover of the casserole; and,

FIG. 7 is a bottom plan view of the casserole alone.
